(57) **CLAIM**

The ornamental design for a license plate frame, as shown and described.

DESCRIPTION

FIG. 1 is a perspective view of a license plate frame showing my new design;

FIG. 2 is a front view thereof;

FIG. 3 is a rear view thereof;

FIG. 4 is a top view thereof;

FIG. 5 is a bottom view thereof;

FIG. 6 is a right side view thereof, wherein a left side view thereof is a mirror image of the right side view;

FIG. 7 is an operational perspective view thereof with a number plate mounted in the license plate frame; and,

FIG. 8 is another operational perspective view thereof with the license plate frame inverted and the licence plate is mounted therein.

The broken lines are for reference only and form no part of the claimed invention.
